CONTROLLING MEANS FOR FLUID MOTORS

Ernest Davis, Syracuse, N. Y., assignor to The Prosperity Company Inc., Syracuse, N. Y., a corporation of New York

Application August 6, 1926, Serial No. 127,714
Renewed August 3, 1933

3 Claims. (Cl. 121—38)

The invention relates principally to a safety control for a garment or ironing press of large size which requires two or more operators. In order to assure that an operator does not have 5 her hands between the jaws of the press when it is closing, control manuals for each operator are provided and the press cannot be closed unless each manual is actuated. The invention also utilizes a master control means or valve 10 which is actuated from the operator actuated control valve or valves.

This invention has for one of its objects a manually controlled mechanism for power motors and particularly for fluid motors having a cylinder and a piston movable therein. A particularly simple controlling means or mechanism is devised requiring both hands of two or more operators to be used in controlling the actuation of the motor means, so that both hands of both or all 15 operators must be occupied during the operation of the machine to which the motor means is applied.

Another object is to construct a control mechanism utilizing a master control valve or means 20 which is operated by operator actuated control means or fluid control valves.

The invention consists in the novel features and in the combinations and constructions hereinafter set forth and claimed.

30 In describing this invention reference is had to the accompanying drawings in which like characters represent corresponding parts in all the views.

Figure 1 is a developed view, partly diagrammatic and partly in section, of this control means.

Figure 2 is a detail view of one of the cylinders and pistons movable therein which is suitable for use with the control means of the invention.

Figures 3, 4 and 5 are sectional views on lines 40 3—3, 4—4 and 5—5 respectively of Figure 1.

Figure 6 is a side elevation illustrating the type of pressing machine to which this actuating mechanism is particularly applicable.

This actuating mechanism is applicable to machines having an opening and closing movement, as garment and laundry presses where a head closes down on a buck to apply pressure to a garment or other article on the buck, and holds its position on the buck indefinitely or during 45 any period suiting the operator. During the closing of the press or the movement of the head toward the buck, the operator is liable to be injured by the head coming down on his hand or fingers and therefore, a two hand control is provided for each operator. The two hand con-

trol of each operator is dependent upon or inter-controlled with the operation of the two hand control of the other operator or operators so that both hands of all operators must be occupied during the closing of the press.

5 The invention comprises an operating mechanism which has a closing and opening movement, the closing movement being performed by a motor, power means or other actuator, and means controlling the actuation of the motor preferably comprising a plurality of pairs of handles, one pair being provided for each operator. The controlling means are so constructed or interrelated with each other that the motor will not be actuated in its closing movement 10 until all of the pairs of handles have been actuated. The invention also includes means for holding the motor means in operated position which preferably take the form of means which holds the master control valve or means in operated position.

15 This operating means or mechanism is particularly adapted to be applied to a pressing machine having a head and a buck of comparatively large area, so that more than one operator is required 20 to operate the machine and a comparatively large motor necessary to apply the necessary pressure, and the motor instead of being one large cylinder is preferably divided up into several, here

25 shown as six cylinders, the six cylinders acting as a single motor. The type of machine to which this invention is applicable is illustrated in Figure 6, and includes a buck 1 mounted on a suitable frame 2, a head 2 carried at the forward 30 end of a yoke or lever 4 pivoted between its ends 35 to an upright 6 rising from the frame, the yoke being connected at its rear end to a motion transmitting mechanism designated generally 7 between the motor means and said yoke. A counterweight 8 is mounted on the rear end of the yoke 40

45 and also countersprings may be used in conjunction with the counterweight. The counterweight and springs are part of the operating means and are practically part of the motor and act to open the press since single acting pistons or motors are preferably used. The machine is closed by the power mechanism to be presently described, and is opened by the counterweight and countersprings.

50 In large pressing machines of the general type above described, but in which the head and buck are of large enough area to press half of a bed sheet, preferably a plurality of yokes 4 are used or in other words there is a duplication of the frame parts and yokes of the 55 general type of machine illustrated in Figure 6.

The motor means comprises preferably a plurality of cylinders 10 each having a piston carried upon a rod movable therein, the rods being connected to the actuating mechanism 7 or some part thereof. The piston 11 is movable in each cylinder and has a piston rod 12 connected to one of the members of the actuating or motion transmitting mechanism 7. The cylinder has heads 13 and 14 at its upper and lower ends and the upper head is provided with a pivoted bearing 15 by means of which it is pivoted to the frame 3, so that the cylinder oscillates during the movement of the piston. The head 13 is provided with an intake port 16 opening into an intake passage 17 and the piston has a valve 18 carried by a stem 19 and projecting in advance thereof, telescoping into the piston and the piston rod against the action of a spring 20. The valve 18 closes, or partly closes, the port 16 so that the air on first entering the cylinder starts to actuate the piston on its out stroke easily. As this port 17 is also an exhaust port, the valve 18 engages and partly closes the exhaust port 16 before the piston reaches the end of its in or upward stroke, so that the air or motive fluid then escapes more slowly and the upward movement of the piston is retarded in order that the head may not open up violently or with the buck terminating in a shock or jar. This form of motor construction is not per se part of the invention.

A packing gland 21 is located in the lower end of the cylinder and is formed with a rabbet having packing means 22, therein, the rabbet and packing coacting with a depending annular skirt 23 on the piston head to seal the joint between the piston head and the cylinder when the piston is at the end of its out stroke, and is holding the press closed. This packing prevents the escape of air while the head is being held closed, the gland 21 is provided with adjustable screws 24 by means of which the gland is adjusted in the cylinder to properly coat with the piston the heads of the said screws resting on the head 14 of the cylinder. The construction of the cylinder and piston per se forms no part of this invention.

The controlling means, by which both hands of each of a plurality of operators must be employed to control the flow of a motive fluid as air to the cylinder or cylinders 10, while the press is being closed, comprises a conduit system including a feed pipe 25, a valve casing 26 connected in the feed pipe, a combined intake and exhaust pipe 27 leading to the cylinder or cylinders, an intake valve 28 or preferably combined intake and exhaust valves 28 and 29 connected together by a stem 30 to act as a unit. The combined valves coat with said casing and are arranged so that the intake valve is normally closed and the exhaust valve 29 open. A plurality of pairs of handles are provided, one pair for each operator, all of which handles must be operated and held operated to close the exhaust valve 29 and hold open the intake valve 28 so that air will pass to the cylinders 10. It further consists in pressure operated means connected in the system to hold the combined valves in their manually operated position as the pistons are completing their power strokes, and thus hold the press closed indefinitely. The invention further includes means operable at the will of an operator to exhaust the pressure operated holding means to permit the return of the parts to their initial position under the influence of the counterweight 8 and countersprings.

As there are several cylinders 10 the combined intake and exhaust pipe 27 is connected to a header pipe 31 from which extend branches 32 to the respective cylinders. Each branch 32 is threaded into the passage 17 in the upper head 13 of its respective cylinder as seen in Figure 2. The intake valve 28 is normally held closed or against its seat and the exhaust valve 29 normally held open or away from its seat by a spring 33. Obviously, from the operation of the combined intake and exhaust valve 28 and 29, air will flow from the feed pipe 25 through the valve casing 26 and through the pipe 27, 31 and 32 to the cylinders and actuate the pistons 11 on their power strokes; and when the intake valve 28 is closed and the exhaust valve 29 is opened, the air can exhaust from the cylinders through the pipes 31, 32 and 27, valve casing 26 and out through space 29a adjacent the exhaust valve 29. The pipe 27 leads from the casing 26 between the valves 28 and 29. In my pending application Sr. No. 671,568 filed October 29, 1923, now Patent No. 1,609,273 the combined intake and exhaust valves are operated by force from a handle applied directly thereto. In my present invention as there are two or more pairs of handles, which must be operated at the same time, the force controlled by these handles is not applied directly to the combined valves 28 and 29, but through a motion transmitting member 34 operated by, or 30 common to all of the handles.

The motion transmitting member 34 is common to all of the manual means for applying force directly to the combined valves 28, 29 or to a stem 35 of the valve, which combined valves are 35 connected to act as a unit through the connecting stem 30.

Two pairs of handles 36 and 37 are provided, both of which pairs must be operated to effect the closing of the press or to actuate the member 34. 40 Two additional pairs of handles 38 and 39 are operable alternately with the pairs 36 and 37, that is either both pairs 36 or 37 must be operated to close the press or both pairs of handles 38 and 39 must be operated to effect the closing 45 of the press. Either the pairs of handles 36 or 37 or the pairs 38 or 39 may be omitted, but in the operation of the machine to which this control system is applied, the operators when ironing some articles as sheets stand at opposite ends of 50 the head and buck so that the handles 36 and 37 are more convenient to operate, and when ironing other shorter articles or in ironing folded sheets the operators stand in front of the machine where the pairs of handles 38 and 39 are more 55 convenient.

The operation of the member 34 is controlled by the pairs of handles 36, 37 through a pressure operated means, which acts on the member 34 to open the intake valve 28 and close the exhaust 60 valve 29, when all the four handles 40, 41, 42, 43 of the groups 36 and 37 are operated. This pressure means comprises a chamber 44 having a diaphragm 45 therein which acts upon a movable rod or plunger 46, which in turn acts on an arm 47 65 of the lever or member 34, the movement of the rod 46 when pressure is applied in the chamber 44 against the diaphragm 45 being against the action of a returning spring 48. The motion transmitting member 34 is a lever pivoted at 70 49. Each of the handles 40, 41, 42 and 43 act upon a normally open exhaust valve to close it. The handle 42 also acts to open an intake valve combined with its companion exhaust valve in a manner similar to the valves 28 and 29. 75

In Figure 3, a normally open exhaust valve 58 is located in a case 51 and connected by a stem 52 to a normally closed intake valve 53 in the casing 51, the exhaust valve having a stem 54 with which the handle 42 coacts. The casing is connected by a pipe 55 to a pipe 56 which is coupled at 57 in the feed pipe 25. A suitable spring 58 holds the valve 53 closed and the exhaust valve 58 open.

10 In Figure 4, an exhaust valve 59 is illustrated as being the form of valve with which each of the handles 40, 41, 43 coact, the exhaust valve being located in a casing 60, which is connected through pipes 61, 62, 63, 64 to the pressure side

15 of the diaphragm chamber 44. Each handle 40, 41, 43 coacts with the stem 65 of the companion exhaust valve 59. It should be noted that an exhaust valve is a connection with a point of atmospheric pressure.

20 In operation, to open the valve 28 and close the exhaust valve 29 through the member 34, two operators must depress all handles 40, 41, 42, 43 and thus close all of the exhaust valves 59 and open the intake valve 53 so that the air flows

25 from the pipe 25 through the pipe 56, pipe 55, casing 51, pipe 66, pipe 63 and pipe 64 to the diaphragm chamber 44 and actuates the diaphragm to rock the lever 34 on its pivot 49, and as this lever acts directly on the stem 35 of the ex-

30 haust valve 29 to close said valve 29 and open the intake valve 28, air passes from the pipe 25 to the cylinders 10 and actuates the pistons 11 on their power strokes. Unless all of the handles 40, 41, 42 and 43 are depressed when the handle

35 42 is operated, the air passing through the valve casing 51 exhausts out through the normally open exhaust valves that have not been operated to their closed position, and hence prevent pressure from building up in the diaphragm chamber 44 sufficiently to actuate the member or lever 34.

The means for holding the press closed or the valves 28 and 29 in their operated position comprises a pressure operated means 67 connected in the conduit system to receive pressure therefrom and hold the member 34 in its operated position after the press has been closed or after the pistons have travelled a predetermined distance, so that it is not necessary for the operators to hold the handles 40, 41, 42 and 43 depressed or operated after the press is closed or substantially closed, or until the piston 11 has travelled a predetermined distance on its power stroke. This means for holding the valve 28 closed and the valve 29 opened is the same in general principle as that set forth in my pending application before referred to. The pressure operated means 67 is a diaphragm chamber 67 having a diaphragm 68 therein, which acts on a plunger 69 which in turn acts on an arm of the lever 34 and this diaphragm chamber is connected in the conduit system through a pipe 70, connected to a port 75, shown in Figure 2, in one or more of the cylinders 10. The port 75 is located to be uncovered by the piston 11 when the piston has travelled a predetermined distance on its power stroke so that back pressure from the cylinder operates the diaphragm 68 to hold the combined valves 28 and 29 in their operated position.

70 As here illustrated, this back pressure is taken from but two of the cylinders 10, and the pipe 70 has branches 72 connected to blocks 73 mounted on the sides of two of the cylinders 10, these blocks 73 having passages 74 therein communicating with ports 75 in the cylinder wall, which

ports 75 are arranged to be uncovered by the pistons when the pistons approach the ends of the power strokes. Obviously, as the pistons do approach or substantially reach the ends of their power strokes, the pressure from the cylinders will pass out through ports 75, passage 74, branches 72, pipe 70 to the diaphragm chamber 67 and actuate the diaphragm 68 and plunger 69 to hold the lever or member 34 in the position it has been actuated by the pressure operated means 44, or the other alternate pressure operated means to be presently described. The diaphragm chamber 67 is here shown as an integral part of the main valve casing 26.

10 Alternate means or handles for effecting the closing of the press and operable, if desired or necessary, alternately with the pair of handles 40, 41, 42, 43 comprise handles 80, 81, 82 and 83 corresponding to the handles 40, 41, 42 and 43, valve casings 84, 85 corresponding to the 15 valve casings 51 and 60, the valve casing 84 having valve construction therein similar to that shown in Figure 3, and the other valve casings having valve construction therein similar to that in Figure 4. The valve casing 84 is connected in the pipe 56 and connected in series with the other valve casings through the pipe 86. The air or pressure passing through the valve casing 84 passes into a pressure operated means 87 similar 20 to the pressure operated means 44, the diaphragm 88 of which acts on a plunger 89 coacting with the lever 34 in a manner similar to that in which the plunger 46 coacts with the arm 47 of the lever 34. Both operators must either actuate the handles 40, 41, 42 or 43 or the handles 80, 81, 82, 83 25 and one operator cannot actuate the handles 40, 41, or 42, 43 and the other operate the handles 80, 81 or 82, 83 or in other words the handles 40, 41 and 42, 43 are grouped together as one operating unit while the handles 80, 81 and 82, 83 30 are grouped together as a second operating unit.

35 The means for effecting the opening of the press by releasing the pressure in the diaphragm chamber 67 includes a handle grouped with each of the other groups of handles. Each handle 90 opens an exhaust valve 91, Figure 5, in a valve casing 92, each casing 92 being connected by a pipe 93 to the pipe 70, which leads into the diaphragm chamber 67. When any one of these 40 handles 90 is operated to open the exhaust valve 91, obviously, the pressure will be exhausted from the diaphragm chamber 67 permitting the main intake valve 28 to be closed by its spring 33, and by the air pressure, and the exhaust valve 29 45 to open so that the air can exhaust out from the cylinders through the pipes 32, 31, 21, valve casing 26 and exhaust port 33 and the press will 50 be opened by its counterweight and counter-spring. 55

60 In operation, both operators must either depress the handles 40, 41, 42 or 43 and hold the same depressed until the press is closed or the pistons near the ends of their power strokes whereupon the back pressure from the cylinders 65 through the pipe 70 to the diaphragm chamber 67 holds the press closed by holding the intake valve 28 open, and the exhaust valve 29 closed. When all of these handles are depressed the normally open exhaust valve in the casings with 70 which the handles 40, 41 and 43 are associated are held closed as is also the exhaust valve in the casing 51 operated by the handle 42, but also the intake valve in the casing 51 is opened so that the air can pass from the main feed line 75

25 to the diaphragm chamber 44, and hence open the intake valve 28 and close the exhaust valve 29, or both operators may operate the handles 80, 81, 82 and 83 and obtain the same result 5 through the pressure chamber 87.

When the press has been held closed by the pressure in the diaphragm chamber 67 long enough to suit the operators, either one of the operators actuates any one of the four handles 10 90, so that the pressure is relieved in the diaphragm chamber 67 and the main intake valve 28 and exhaust valve 29 permitted to close under the influence of the spring 33 and the exhaust valve 29 to open, so that the pressure in the cylinders 15 can exhaust from the cylinders and the parts return to their starting position under the influence of the counterweight and countersprings.

Although the control means described herein is primarily intended to be used with a plurality 20 of pairs of control handles or means, the construction is also suitable as a new and novel control utilizing a master controlled means or valve 26 which is controlled by the motive power or fluid through primary control means or valves 42 25 and 43 with or without the other primary control valves 40 and 41. These control valves are connected with the source of fluid supply which actuates the motor means and the fluid pressure means or diaphragm 45 to actuate the master 30 control valves 28 and 29.

This invention is particularly advantageous in that it provides a particularly simple and efficient means by which both hands of each of two or more operators must be used to effect the closing 35 of a dangerous press.

What I claim is:

1. The combination of a single acting fluid motor comprising a cylinder, a piston movable in the cylinder, means for controlling the flow of 40 motive fluid to and from the cylinder comprising a conduit system including a feed pipe, a valve casing connected in said pipe, a combined intake and exhaust pipe connecting the valve casing with the cylinder, an intake valve and an exhaust 45 valve in the valve casing normally arranged so that the intake valve is closed and the exhaust valve open, pressure operated means for operating the valves and including a motion transmitting member common to said valves and opera-

tively connected thereto, supply pipes connected to the pressure operated means and to the feed pipe, valves for controlling the flow of fluid from the feed pipe through the supply pipes to the pressure operated means, a second pressure operated means connected in said system and co-acting with said motion transmitting member to hold the intake and exhaust valve in operated position, and means for releasing the pressure from said pressure operated means. 10

2. The combination of a cylinder, a piston movable in the cylinder, a conduit system for a motive fluid including a feed pipe, a valve casing in the feed pipe, a combined inlet and exhaust pipe leading from the valve casing to the cylinder, 15 combined intake and exhaust valves in the valve casing, pressure operated means and pipes connected said pressure operated means to the feed conduit, operator-operated valves for controlling the flow of fluid from the feed conduit to the 20 pressure operated means through said pipes, a motion transmitting member between the pressure operated means and said combined valves, a second pressure operated means coacting with said motion transmitting member and also connected in the conduit system to hold said combined valves in their operated positions, and means for releasing the pressure from the pressure operated means. 25

3. The combination of a motor, means for controlling the operation of the motor, a combined intake and exhaust master valve normally arranged with the intake closed and the exhaust open, fluid operated means for actuating the master valve, a feed conduit for the fluid, two 30 pairs of normally open exhaust valves in the feed pipe, the valves of each pair being grouped together, a normally closed intake valve associated with one of the exhaust valves of one of the pairs, a manual for each exhaust valve of the 35 pair, one of said manuals for exhaust valve acting as a manual for the intake valve associated therewith, means controlled by the operation of the motor for holding the master valve in its operated position, and a release valve for the holding means grouped with one of the pairs of the valves. 40 45

ERNEST DAVIS.
